UNITED STATES PATENT OFFICE.

SARAH K. OGDEN, OF FORT SCOTT, KANSAS.

FLOUR-SIFTER.

SPECIFICATION forming part of Letters Patent No. 586,106, dated July 13, 1897.

Application filed August 25, 1896. Serial No. 603,903. (No model.)

To all whom it may concern:

Be it known that I, SARAH K. OGDEN, of Fort Scott, Bourbon county, Kansas, have made certain new and useful Improvements 5 in Flour-Sifters, of which the following is a full, clear, and exact description, reference being had to the accompanying drawings, forming a part hereof.

My invention relates to flour-sifters; and 10 my object is to produce a device of this character whereby considerable time, labor, and material are saved in operation, as hereinafter explained, and which will serve also the purpose of a temporary receptacle for flour.

15 A further object of the invention is to produce a sifter of this character which combines simplicity, durability, and cheapness of manufacture and from which the discharge of flour can be regulated or controlled.

20 To these ends the invention consists in certain novel and peculiar features of construction and combinations of parts, as will be hereinafter described and claimed.

In order that the invention may be fully 25 understood, I will proceed to describe it with reference to the said accompanying drawings, in which—

Figure 1 represents a central vertical section of a flour-sifter embodying my invention.

30 Fig. 2 represents a vertical central section taken in a plane at right angles to the first-named figure and showing also in elevation the connection between the push-rod and the crank-arm of the rock-shaft which carries 35 the door or valve normally closing the bottom of the casing. Fig. 3 shows an enlarged detail perspective view of a part of the device hereinafter to be described.

Similar reference-numerals designate cor- 40 responding parts in the several views.

Referring now to the drawings in detail, 1 designates a cylindrical casing provided with a handle 2 of the type shown or of any other suitable or preferred construction. A short 45 distance above its lower margin it is provided with a bottom consisting of downwardly-converging plates or deflectors 3 and the door or valve 4, which bridges the opening formed between the lower margins of said deflectors.

50 One edge of said valve overlaps the upper side of one deflector 3, while its opposite edge underlaps the under side of the companion

deflector 3, as shown clearly in Fig. 2. At its middle it is mounted rigidly in any suitable manner upon the diametrically-arranged 55 rock-shaft 5, which is journaled at its opposite ends in the casing, and is provided at the end below the handle 2 with the crank-arm 6, the arrangement being such that when said crank-arm is depressed to the position shown in dotted lines, Fig. 2, the valve 4 swings in the direction indicated by the arrows to the position also shown in dotted lines, same figure, so that the flour contained in the casing may pass through the opening 65 thus uncovered.

7 designates a vertical push-rod which extends through the handle 2 and also through the brace-plate 8. It is pivotally connected to the crank-arm and is provided at its upper 70 end with a head 9, upon which one's thumb may be placed to operate the valve, as described.

In order to hold the valve normally closed, the spiral expansion-spring 10 encircles the 75 rod 7 and bears at its lower end upon the plate 8 and is secured at its upper end to said rod by projecting it through an opening therein or in any other suitable manner. By this arrangement the valve is held in its closed position with the head 9 of the push-rod some 80 distance above the handle, and after each depression of said rod and consequent opening of the valve said spring automatically returns them to their original positions.

85 Arranged within the casing, about midway its height, preferably, is a sieve 11 of the customary semicircular or segmental form. Said sieve is provided with a stiffening-band 12 at its upper margin, of sheet metal, and projecting radially outward from said band and through a circular opening in the wall of the casing and at right angles, preferably, to the rock-shaft 5 is the tube or sleeve 13, and secured vertically to or cast integral with said 90 sleeve at its outer end is the arm 14, whereby the position or movement of the sieve may be determined, as will be hereinafter explained.

The rotary beater or stirrer for the flour, which operates in conjunction with the sieve, 95 is constructed as follows:

15 designates the shaft. It is journaled at one end in the sleeve 13 and is provided at said end with a crank-arm 16 and is journaled

at its opposite end, as at 17, in the casing at a point diametrically opposite to said sleeve. It also extends rotatably through the band 12 of the sieve.

5 18 designates the radial arms of the beater, which are curved to conform approximately with the sieve 7 in the customary manner.

By the construction thus described it is obvious that the beater may be rotated by turning the crank 16 and that the position of the sieve may be reversed—that is, it may be rotated upon the shaft 15. In order to limit this rotatable movement, however, the stop-pin 19 projects inwardly of the casing, as

15 shown in Fig. 1, and this stop-pin is adapted to be engaged at one side or the other by the band of the sieve, accordingly as the beater is rotated in one direction or the other. That is to say, when the sieve is in the position

20 shown in full lines, Fig. 1, the beater must be rotated in the direction indicated by the arrow, full lines, and when thus rotating the tendency of the sieve is to revolve in the same direction through the frictional relation of the

25 sleeve 13 and shaft 15; but this tendency, it will be observed, is resisted by said stop-pin. When the sieve is in this position, the flour is sifted down onto the bottom of the casing.

In order, however, that the flour may be re-30 sifted without removing it from the casing, I have provided a removable top 20, which closes the upper end of the casing. This top is provided with a marginal flange which embraces the casing and at diametrically oppo-

35 site points is provided with an aperture 21, to engage the outwardly-projecting pin 22 of the casing, and the lug 23, to be engaged by the spring-catch 24, secured to the casing and inclosed by a keeper 25. This top or

40 cover 20 is adapted to form temporarily the bottom of the casing when the latter is in-

verted and when the sieve occupies its re-

45 versed position, as indicated by dotted lines in Fig. 1. When in such inverted position,

the beater is rotated in the direction indi-

cated by the dotted arrow, Fig. 1, and conse-

quently causes the flour previously sifted onto

the natural bottom of the casing to pass down

50 through the sieve onto the temporary bottom

or cover 20. It may now be again resifted

by inverting the casing, or rather bringing it

to its upright position. Immediately there-

after, or before the sifting operation begins,

the crank-handle is grasped and rotated in

55 the direction indicated by the arrow, full

lines, and this causes the sieve to swing back

to its normal pendent position, as shown in

full lines, Fig. 1. The continued movement

of the beater or stirrer in the same direction

60 now, of course, sifts the flour through the

sieve onto the natural bottom of the casing.

By inverting the casing again and changing

the direction of rotation of the crank-arm

the sieve is again temporarily reversed and

65 the flour sifted down onto the top or cover 20,

forming the temporary bottom. By again

bringing the casing to upright position and re-

versing the movement of the crank the sieve is again brought back to its original position and the flour sifted onto the natural bottom 70 of the sieve, as will be readily understood.

It will be seen from the foregoing that the flour may be sifted and resifted as many times as desired, the only manipulation necessary being to reverse the position of the casing 75 and turn the crank-handle in the opposite direction. The slight frictional relation between the sleeve 13 and shaft 15 is sufficient when the movement of the crank is reversed to revolve the sifter also until it comes in contact with said stop-pin, as will be readily understood. After the flour has been thoroughly sifted it is only necessary for the operator to hold the casing over the point or receptacle to receive the flour and press upon the head 80 9 and depress the push-rod. When this is done, the flour passes through the opening formed by swinging the valve to the position shown in dotted lines. By depressing the push-rod more or less the quantity escaping 85 90 may of course be regulated. If it be desired to permit the flour to pass very lightly into the receptacle, the valve may be opened, as before explained, and the flour sifted down through said opening. It will be apparent, 95 also, that I may dispense with the valve and its operating mechanism, and in lieu thereof provide the casing with a permanently-closed bottom. In this case the flour, as before, will be introduced into the casing from above and 100 then sifted down upon the bottom. The casing will then be inverted and the position of the sieve reversed by reversing the movement of the crank - handle, as hereinbefore explained, and the flour sifted down upon the 105 top or cover 20, forming temporarily the bottom. While in such position said temporary bottom may be removed and the flour deposited where required, or the flour may be sifted back and forth as many times as desired, and 110 then emptied from the casing in the same manner.

By this construction it is obvious that it is necessary that the flour be sifted at least twice, but it is also obvious that a much 115 cheaper flour-sifter is produced. This operation, of course, may be performed with the construction illustrated—that is, the flour may be introduced into the casing, sifted back and forth as many times as required, and then dis-120 charged from the upper end by simply inverting the casing. If it be desired, however, to simply sift the flour once, it will be necessary to employ a casing having an open top and a bottom which may be opened, as shown 125 in the drawings.

To secure the top or cover 20 in place, it is only necessary to slip the opening 21 upon the pin 22 and then force the cover downward so that the beveled surface of the lug 23 shall 130 cause the spring-catch 24 to yield outwardly until said spring-catch clears the upper end of said lug, and swinging inwardly locks the cover against accidental displacement.

To remove the cover, it is only necessary to press the catch outwardly with one's thumb and lift it from the casing.

By forming the bottom with inclined or de-

5 flecting sides it is obvious that all of the flour may be easily dislodged and caused to pass through the opening of the bottom when the valve is opened by the depression of the push-bar.

10 It is obvious from the foregoing that I have produced a flour-sifter which will be found to possess decided advantages over any at present on the market with which I am acquainted.

15 In the first place all sifters up to the present time have been open at both top and bottom and consequently when carried from the flour bin, barrel, or sack to the table a certain quantity would sift through upon the floor, and when placed upon the table the 20 slight jar incident to such disposal would cause a second small quantity to sift down upon the table, and this waste continuing day after day in time amounts to considerable. Also when making angel-food and other fine 25 cakes where the flour must be sifted and re-sifted a number of times it has been necessary to sift the flour through the receptacle, then pour it back into the top of the sifter, sift it through again, replace it in the sifter, 30 and sift it through again, and so on, at a slight loss of material each time and at a considerable loss of time and labor. My sifter is designed to obviate this waste of material, time, and labor, as the casing having a normally-closed bottom may receive the flour 35 and be carried across the room and placed upon the table without any loss, and it may then be sifted back and forth a dozen times with less labor and in a shorter space of time 40 than it can be sifted twice in the old way above described.

It is to be understood that meal or any other finely-ground product may be used with this sifter as well as flour.

45 It is also to be understood, of course, that slight changes in the detail construction, form, or arrangement may be made without departing from the spirit and scope of my invention or sacrificing any of the advantages thereof.

Having thus described the invention, what I claim as new, and desire to secure by Letters Patent, is—

55 1. A flour-sifter, comprising a reversible casing, provided with a reversible sifter, and a rotary beater or stirrer, substantially as described.

60 2. A flour-sifter, comprising a reversible casing, having a pin projecting inwardly thereof, and provided with a reversible sieve which is adapted to engage one side or the opposite side of said pin, and a rotary beater operating in conjunction therewith.

65 3. A flour-sifter, comprising a reversible casing, having a pin projecting inwardly thereof, and provided with a bottom and a removable top, a reversible sifter mounted

therein and adapted to engage one side or the opposite side of said pin, and a rotary beater adapted to operate in conjunction with said 70 sifter.

4. A flour-sifter, comprising a reversible casing, provided with a bottom and a removable top which forms at times a temporary bottom, a pin projecting inwardly from the 75 casing, a reversible sieve within the casing and adapted to engage one side or the other of said pin, and a rotary beater operating in conjunction with said sieve, and provided externally of the casing with a crank-handle, 80 substantially as described.

5. In a flour-sifter, the combination of a reversible casing, having a pin projecting inwardly, a bottom and a removable top, a reversible sifter therein provided with a sleeve 85 extension which is journaled in the casing, and a rotary sifter journaled in the casing and in said sleeve, and adapted when rotated in one direction to revolve the sifter until it comes in contact with said pin, and adapted 90 when rotated in the opposite direction to swing the sifter back to its original position, where it engages the opposite side of said pin, substantially as described.

6. In a flour-sifter, the combination with a 95 reversible casing, provided with a bottom and a removable top which forms at times a temporary bottom, a pin projecting inwardly from the casing, a reversible semispherical sieve within the casing and dividing it into two 100 chambers which communicate only through said sieve, and adapted to engage one side or the other of said pin, and a rotary beater operating within the semispherical sieve at all times, and provided externally of the casing 105 with a crank-handle, substantially as described.

7. A flour-sifter, comprising a suitable casing having a handle, a sieve, a beater, and provided with a bottom consisting of a pair 110 of oppositely-disposed plates and an oscillatory valve bridging the space between said plates, a rock-shaft extending longitudinally of and carrying said valve and journaled in the casing, a push-rod extending vertically 115 through the handle and pivotally connected to a crank-arm at one end of the rock-shaft, and a spring holding said push-rod normally elevated, substantially as described.

8. A flour-sifter, comprising a suitable cas- 120 ing, having a handle, a sieve, and beater, and provided with a bottom consisting of a pair of oppositely-disposed plates and an oscillat- 125 ing valve bridging the space between said plates, a rock-shaft extending longitudinally of and carrying the valve, and journaled in the casing, a push-rod extending vertically through the handle and pivotally connected to a crank-arm at one end of the rock-shaft, a spring holding said push-rod normally ele- 130 vated, and a removable top or cover for the casing, substantially as described.

9. A flour-sifter, comprising a suitable cas- 130 ing having a handle, a reversible sieve, and

beater, and provided with a bottom consisting of a pair of oppositely-disposed plates and an oscillating valve bridging the space between said plates, a rock-shaft extending longitudinally of and carrying the valve, and journaled in the casing, a push-rod extending vertically through the handle and pivotally connected to a crank-arm at one end of the rock-shaft, and a spring holding said push-

rod normally elevated, substantially as described.

In testimony whereof I affix my signature in presence of two witnesses.

SARAH K. OGDEN.
